The ornamental design for a multi functional moated food bowl, as shown and described.

DESCRIPTION

FIG. 1 is an exploded isometric view of a multi functional moated food bowl;

FIG. 2 is a top plan view of the multi functional moated food bowl seen in FIG. 1 in a platform configuration;

FIG. 3 is a front elevational view thereof, the rear, left and right elevational views being a mirror image thereof;

FIG. 4 is a bottom view thereof;

FIG. 5 is a top plan view of the multi functional moated food bowl seen in FIG. 1 in a bowl configuration;

FIG. 6 is a front elevational view thereof, the rear, left and right elevational views being a mirror image thereof; and,

FIG. 7 is a bottom view thereof.

The claimed multi functional moated food bowl is used to keep ants and other crawling insects away from food placed therein while in a platform or bowl configuration.

The broken lines depict portions of the food bowl that form no part of the claimed design.
